UNITED STATES PATENT OFFICE.

CHARLES H. PERKINS, OF PROVIDENCE, RHODE ISLAND.

IMPROVEMENT IN ROLLING-MILLS.

Specification forming part of Letters Patent No. 128,422, dated June 25, 1872.

To all persons to whom these presents may come:

Be it known that I, CHARLES H. PERKINS, of the city and county of Providence, of the State of Rhode Island, have invented a new and useful Improvement in "Rolling-Mills," or machinery for rolling iron or other metal; and do hereby declare the same to be fully described in the following specification and represented in the accompanying drawing, of which—

Figure 1 is a front elevation; Fig. 2, an end view; and Fig. 3, a vertical and transverse section, of three pairs of reducing-rolls, with their supports and operative mechanism, with my invention applied to such rolls, which are of the kind used for rolling iron into flat bars, either square or rectangular, in transverse section, the upper roll of each pair being extended within its fellow-roll, in the manner as shown.

In rolling a metal bar by rolls of the kind described and shown there will be what are termed "fins" raised on its upper surface at its opposite edges, such being due to the pressure on the metal between the continuous vertical edges of the reducing parts of the rolls. To reverse or turn the bar the bottom side up while passing from one pair of rolls to the next pair, so that what was first the upper or fin side of the bar in passing between the first pair may become the lower side of it in passing between the next pair, is the object of my invention, the same being to effect the removal of the said "fins" from the bar.

In carrying out my invention I combine with each pair of the reducing-rolls and the next succeeding pair a guide passage or tube in the form of a semicircular arc, or thereabout. The said passage or tube I term the "reversing-guide," it being hereinafter more particularly explained.

In the drawing, A denotes the frame for supporting the several pairs B B' C C' D D' of rolls, they being arranged relatively to one another and provided with suitable operative

mechanism, all as represented. The reversing-guides are exhibited at E E', one being extended from the bite of the lowermost pair of rolls B B' to that of the next rolls C C'. The other reversing-guide E', arranged on the opposite side of the machine, extends from the bite of the rolls C C' to that of the rolls D D', all being as represented.

Figs. 4 and 5 are views of the two sections or parts of each of the inside reversing-guides. Fig. 6 is a transverse section of such two parts taken through their supports. One of the parts is fastened directly to the frame and the other is secured to the fellow part by keys *k k* going through studs *ll* projected from the supporting-ears *m m* of the stationary part, and also through those *n n* of the movable part, all being as shown in the drawing.

When two reversing-guides are arranged with three pairs of rolls in the manner as shown they form a serpentine passage leading from the first to the second pair and from the latter to the third pair, whereby a bar of iron will be guided from the first pair to the second and turned over in the mean time, and next be guided from the second pair of rolls to the third pair and be turned over while passing from the said second to the said third pair.

The arrangement of the three pairs of rolls and the two reversing-guides saves the employment of a fourth pair of rolls, which would or might otherwise be necessary provided the two guides were disposed in separate frames with a pair of rolls to each.

I claim as my invention—

The combination and arrangement of the two reversing-guides E E' with the three pairs of rolls B B', C C', and D D', all being to operate substantially in manner as described.

CHARLES H. PERKINS.
